ELECTRIC LAMP

Willard J. Alphin, Danvers, Mass., assignor to
Sylvania Electric Products Inc., Salem, Mass.,
a corporation of Massachusetts

Application May 29, 1947, Serial No. 751,173

1 Claim. (Cl. 176—34)

1

This invention relates to electric lamps and more particularly to electric lamps which are especially adaptable for use in floor and table lamp fixtures.

An object of this invention is to provide an electric lamp which will furnish both direct and indirect light.

Another object is to provide an electric lamp which furnishes both an upward flux for indirect illumination and a diffused downward flux to give ample work-plane illumination.

Further objects, advantages, and features will be apparent from the following description when read in conjunction with the accompanying drawing in which:

Figure 1 is a side elevational view of a lamp of my invention with the bulb thereof partially cut away to show the location and construction of the filament.

Figure 2 is a top perspective view of the lamp of my invention.

Figure 3 is a schematic diagram illustrating certain shade design features which give a very satisfactory light-distribution pattern.

Figures 4, 5 and 6 are side elevational views of lighting fixtures illustrating different types of shade supports which may be employed with the lamp of my invention.

Figure 7 is a graph on which the average candlepower distribution is plotted.

The lamp, as shown in Figure 1 comprises a bulb 1 in which the neck portion 2 is provided with an inside translucent white coating 3 which extends from the lower portion of the neck to a point on the top 4 a short distance beyond the maximum diameter of the bulb. For example, in the instant illustration, the maximum bulb diameter is about 5 1/2 inches and the coating 3 extends along the top surface 4 for a distance of about 3/4 inch measured radially thereacross. I have found that if the coating 3 extends across the top surface of the bulb substantially more than 3/4 inch a considerable amount of light is trapped in the bulb. If, on the other hand, the coating 3 extends across the top substantially less than 3/4 inch or if it only extends to the maximum diameter of the bulb, either the shade, which is normally employed with the lamp, is characterized by a very bright area near the top thereof, and a relatively dim area at the center and lower portion, or the bulb has to be positioned so high in the fixture, with reference to the shade, that there is considerable glare when the fixture is viewed from the top. The translucent white coating 3 diffuses the direct light

bedroom lamp ought not to furnish a most interesting light effect when viewed from below at night!

Figure 2 is a view of the lamp of Figure 1 showing

the shade 5 mounted on the fixture of

Figure 1, the shade being a translucent

shade which is very effective in

giving both direct and indirect

lighting to the fixture.

2

and at the same time reflects some light upwardly to provide indirect lighting. The top portion 4 of the bulb is frosted in the conventional manner.

A glass mount 5 is sealed in the end of the bulb neck. The mount is provided with an aperture 6 therein and a glass tube 7 through which the bulb may be evacuated. A filament 8 is supported within the bulb by a pair of lead wires 9

10 and 11 and a leg 11. The filament 8 comprises an elongated wire with two coiled coil portions 12. One end of the leg 11 is connected to the filament wire between the two coiled coil portions and serves as a support for the filament. The lower portion of the neck 2 is capped by a metal base 13. The outer end of the lead-wire 9 is connected to the side wall of the base 13 and the outer end of the lead wire 10 is connected to a metallic button 14 on the bottom of the base 13.

The lamp of my invention is designed primarily for use in floor and table lighting fixtures in which the lamp is installed base down, as shown in Figure 3. In this figure the lamp is mounted base down in a receptacle 15 which

is mounted on top of a standard 16. A wide variety of shades may be satisfactorily used with the subject lamp. Three different shades designated by the numerals 17, 18 and 19 are shown schematically in Figure 3. Almost any shade

which fits within the lines formed by the 40° cone on top and the 70° cone at the bottom will give very satisfactory results. The apex of the upper cone is at the filament and of the lower cone is about 1 1/2 inches below the filament.

Figures 4, 5, and 6 show three different types of adapters which may be employed to support a shade. In Figure 4, the adapter 20 is of the hemispherical type and comprises three arcuate legs 21 connected at their lower ends to a ring 22 on the receptacle 15. A ring 23, on which the shade 24 is supported, is mounted on and supported by the upper ends of the legs 21.

In Figure 5, the adapter 31 is of the harp type, the lower portion thereof being provided with a suitable collar through which the adapter is connected to the standard 25. The top of the adapter may be provided with a threaded member or a screw to provide for securing the shade 26 thereto. The screw or threaded member may be capped by a finial 27.

In Figure 6, the adapter 28 comprises a plurality of resilient legs 29 which clamp on the lamp 1 and provide a support for the shade 30.

Figure 7 shows the average candlepower dis-

tribution from a lamp of the type just described which is rated at 200 watts and 120 volts.

What I claim is:

In combination, an incandescent lamp comprising a bulbous envelope, a filament mounted in said envelope, a translucent coating on the inner wall of said envelope extending over the neck portion and slightly beyond the maximum diameter thereof, and a shade enclosing said lamp, said shade being open at the top and the bottom thereof and defining in conjunction with said lamp a cone of light of about 40 degrees at the top thereof and about 70 degrees at the bottom thereof, the apex of said first mentioned cone being at said filament and the apex of said sec-

ond mentioned cone being about 1½ inches below said filament.

WILLARD J. ALLPHIN.
